UNITED STATES PATENT OFFICE.

JOHN WILBURN BUTTS, OF ATLANTA, GEORGIA.

WATER SYSTEM AND PUMP CONTROL.

1,097,529.

Specification of Letters Patent. Patented May 19, 1914.

Original application filed July 21, 1913, Serial No. 780,276. Divided and this application filed October 22, 1913. Serial No. 796,697.

To all whom it may concern:

Be it known that I, JOHN W. BUTTS, a citizen of the United States, residing at Atlanta, in the county of Fulton and State 5 of Georgia, have invented a new and useful Water System and Pump Control, of which the following is a specification.

The object of the present invention is to provide novel means for suspending a pump 10 in a well or other source of supply, and to provide novel means for operatively connecting the pump with the driving mechanism therefor.

The present application contains matter 15 divided out of my co-pending application, Serial No. 780,276, filed July 21, 1913, for Letters Patent upon a water system.

It is within the scope of the invention to improve generally and to enhance the utility 20 of devices of that type to which the present invention appertains.

With the above and other objects in view which will appear as the description proceeds, the invention resides in the combination 25 and arrangement of parts and in the details of construction hereinafter described and claimed, it being understood that changes in the precise embodiment of the invention herein disclosed can be made 30 within the scope of what is claimed without departing from the spirit of the invention.

In the accompanying drawing, the preferred embodiment of the invention is shown in a single sectional view, wherein 35 sundry parts appear in elevation.

In the accompanying drawing, the numeral 1 indicates a well or other source of water supply. Mounted adjacent the well 1 is a supporting structure including piers 2 carrying bearings 3 in which is journaled 40 for rotation a drive shaft 4. Supported upon a bracket 5 projecting from one of the piers 2, or in any other desired manner, is an electrical motor 6. Intermeshing 45 pinions 7 connect the armature shaft of the motor 6 with the drive shaft 4. Secured to the drive shaft 4 are grooved pulleys 8 about which are trained belts 9 passed around pulleys 10 secured to a shaft 11 50 journaled in bearings 12 carried by a pump 14 located in the well 1. The shaft 11 includes a crank 15 which is connected with the plunger 16 of the pump 14 through the instrumentality of a pitman 17. A flexible 55 element 18 is secured as indicated at 19

to the pump 14 and is carried upwardly around a pulley 20 journaled for rotation on the drive shaft 4, the free depending end of the flexible element 18 carrying a plurality of individually removable weights 21. 60

Vertically disposed pipes 22 and 23 are provided, the pipes being closed at their upper ends as shown at 24. The pipes 22 and 23 are mounted to slide in collars 25 which may be carried on brackets 26 connected with the piers 2, or supported in any other suitable manner. The pipe 22 is provided with a branch 27 communicating with the upper portion of the cylinder of the pump 14. Projecting from the 70 branch 27 is an inlet 28 and projecting from the inlet 28 is a branch 29 which communicates with the lower portion of the cylinder of the pump 14. Projecting from the cylinder of the pump 14 is a branch pipe 30, 75 communicating with the pipe 23 and extended from the upper portion of the cylinder of the pump. Another branch 31 projects from the lower portion of the cylinder of the pump 14 and communicates with the 80 lower end of the pipe 23. In the branches 27, 29, 31 and 30 check valves 32 may be interposed. Communicating with the pipe 23 is a main pipe 33 entering a building 34. At this point it may be stated that 85 any number of connections may be provided, but, for the sake of illustration, it will be presupposed that one building is supplied, the foregoing supposition being entertained merely for the purpose of simplifying the drawings. The main pipe 33 communicates with a faucet 35, indicated 90 diagrammatically in the drawings. A conductor 47 leads from the motor 6 to the faucet 35 and by manipulating the faucet, 95 the electrical circuit including the conductor 47 and the motor 6 may be opened and closed.

When the motor 6 is put into operation in the manner above described, the intermeshing pinions 7 will transmit motion to the drive shaft 4, the latter through the pulleys 8 and the belts 9 transmitting motion to the shaft 11, the crank portion of which, through the medium of the pitman 17 will operate the 100 plunger 16 of the pump 14. The pump is a double acting one and when in operation, water will be drawn inwardly to the inlet 28, through the branches 27 and 29, the water 105 passing outwardly through the branches 30 110

and 31 into the pipe 23 and from the pipe 23 by way of the main pipe 33 to the faucet 35.

It is to be observed that the belts 9 not only serve as a means for actuating the pump 14, but, as well, also constitute the sole means for suspending the pump in the well 1.

The weights 21 may be increased or decreased in number, thus increasing or decreasing the tension on the flexible element 18, the lower end of which is connected as shown at 19 to the pump 14. The flexible element 18 it will be recalled, passes over the pulley 20 which is journaled on the drive shaft 4, and by changing the number of weights 21, the tension of the supporting and actuating belts 9 may be regulated. The pipes 22 and 23, sliding into collars 25, act as guides to direct the vertical movement of the pump 14 when the position thereof in the well 1 is adjusted.

Having thus described the invention, what is claimed is:—

1. In a device of the class described, a supporting structure; a drive shaft journaled thereon; an actuating shaft; a pump suspended from the actuating shaft; means for operatively connecting the actuating shaft with the pump; and a belt connecting the shafts, the belt constituting the sole means for supporting the pump against vertical movement.

2. In a device of the class described, a supporting structure; a drive shaft journaled thereon; an actuating shaft; a pump suspended from the actuating shaft; means for operatively connecting the operating shaft with the pump; a flexible element connected with the pump; means for supporting the intermediate portion of the flexible element; a weight carried by the flexible element; and a belt operatively connecting the shafts.

3. In a device of the class described, a supporting structure; a drive shaft journaled thereon; an actuating shaft; a pump suspended from the actuating shaft; means for operatively connecting the pump with

the actuating shaft; a belt trained about the shafts, and constituting means for supporting the pump; and a guide secured to the pump, the guide being slidably received in the supporting structure. 50

4. In a device of the class described, a supporting structure; a drive shaft journaled therein; an actuating shaft; a belt connecting the shafts and constituting means for supporting the actuating shaft; a pump supported by the actuating shaft; means for operatively connecting the operating shaft with the pump; a guide member secured to the pump; and a fixed guide in which the guide member is slidably received. 55

5. In a device of the class described, a supporting structure; a drive shaft journaled therein; an actuating shaft; a pump supported upon the actuating shaft; a belt connecting the shafts and constituting means for supporting the actuating shaft and the pump; a flexible element secured to the pump; means for supporting the flexible element intermediate its ends; a weight on the free end of the flexible element; a guide member secured to the pump; and means for supporting the said guide member slidably. 70 75

6. In a device of the class described, a supporting structure; a drive shaft journaled for rotation therein; an actuating shaft; a pump suspended from the actuating shaft; means for connecting the pump with the actuating shaft; a belt connecting the shafts and constituting means for supporting the actuating shaft and the pump; a pipe connected with the pump and constituting a part of the circulating system of the pump; 80 85 and means for receiving the pipe slidably, whereby the pipe will constitute a guide for the pump.

In testimony that I claim the foregoing as my own, I have hereto affixed my signature 90 in the presence of two witnesses.

JOHN WILBURN BUTTS.
